Primary Examiner — Kevin K Rudzinski*Assistant Examiner* — Amber J Rabie(74) *Attorney, Agent, or Firm* — Sterne, Kessler, Goldstein & Fox PLLC.(57) **CLAIM**

The ornamental design for a shoe, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top front perspective view of a shoe showing the claimed design;

FIG. 2 is a left side view thereof;

FIG. 3 is a top view thereof; and,

FIG. 4 is an enlarged view of the area shown within the dot-dot-dash broken lines in FIG. 2.

The dot-dash broken lines in the figures and the areas outside of the dot-dash broken lines show portions of the shoe that form no part of the claimed design.

The dot-dot-dash broken lines in the figures form no part of the claimed design.

1 Claim, 4 Drawing Sheets
(4 of 4 Drawing Sheet(s) Filed in Color)
